NELSON JOHNSON, OF JASPER, NEW YORK.

Letters Patent No. 88,176, dated March 23, 1869.

IMPROVEMENT IN SAW-GUMMERS.

The Schedule referred to in these Letters Patent and making part of the same.

To all whom it may concern:

Be it known that I, NELSON JOHNSON, of Jasper, in the county of Steuben, and State of New York, have invented certain new and useful Improvements in Saw-Gummers; and I do hereby declare that the following is a sufficiently full, clear, and exact description thereof, to enable one skilled in the art to which my said invention appertains to make and use it, reference being had to the accompanying drawings, which are made part of this specification.

My invention relates to certain improvements in machines, or tools for gumming saw-teeth; and

It consists—

First, in the provision of a suitable bail for supporting the device on the saw, and a novel arrangement of the clamping-screws; and

Second, in mounting the gumming-roller, or cutter in a laterally-adjustable frame, so as to adapt it to be readily used for its entire length.

In the drawings—

Figure 1 is a plan view of a saw-gummer embodying my improvements.

Figure 2 is a sectional elevation of the same, in position on the saw, the plane of section being indicated by the line $x-x$, fig. 1.

Figure 3 is a perspective view of an Emmerson gummer, provided with a modified form of my supporting-bail.

The stock of my improved gummer, figs. 1 and 2, may consist of a plate, or frame, A, of proper shape to adapt it to support the cutter, provided with rearwardly-projecting arms A¹ A¹, for the reception of the attaching and supporting-devices, and in front with a suitable handle A², by which to hold it up against the tooth; all of which parts may readily be cast in one piece, as represented.

B is a rectangular frame, or carriage, provided with suitable bearings for the reception of the gumming-roller, or cutter C, and a screw, D, and adapted to slide within ways a a, on the stock A, said ways having a dovetail, or other suitable form, in cross-section, as represented in fig. 2, to support the frame against vertical displacement.

The cutter C is composed of hardened steel, provided with the usual burr, and either of straight or spiral form.

One of its pivots e is extended, and provided with an angular end, e', for the reception of a crank by which to operate the cutter.

The screw D is held from longitudinal displacement in the end-piece a* of the way of the cutter-carriage B, and engaging with the female screw in said carriage, adjusts the carriage as desired, by its rotation, it being provided with a thumb, or other suitable head, d, by which to turn it.

The rearwardly-projecting arms of the stock are separated by a slot, E, of sufficient width for the reception of the greatest thickness of saw which the stock is adapted to operate on, and which extends a

sufficient distance in front of the cutter to admit of the different forms of teeth being introduced, in the manner shown in fig. 2.

The separate arms are further provided with slots a' for the reception of a bail, F, and with a number of transverse perforations a* for the reception of thumb-screws G G'; that part of the arms outside of the slot a' only, however, being threaded for the reception of said screws, and themselves partially unthreaded, as represented in fig. 1.

These screws clamp the saw-blade, and by their number and arrangement, serve to effectually prevent any "wabbling," or "reeling" of the tool during its operation, which movement tends to make an irregular and rounded edge, and which cannot be prevented with a single pair of clamping-screws. A number of perforations is provided for the reception of the screws, as shown in fig. 2, so as to allow their position to be adjusted to suit different sizes of saws.

The bail F may be formed in one piece, of wrought-iron or other suitable metal, and is formed with a V-shaped, or chisel-edge, f, for its bearing-surface, and its widened extremities are provided with a number of corresponding perforations f', for the reception of its attaching-screws, which may be either G, as shown, or G'.

The bail, being adjusted to suit the size of saw which is to be gummed, by means of the perforations a* f', is applied to the saw, as represented in fig 2, resting on the back of the tooth, or on the blade in rear thereof, its sharp bearing-edge adapting it to hold in whatever position placed.

The object of the bail is to support the tool against drifting down and back under the pressure requisite in gumming the tooth, the clamping-screws usually employed having been found entirely inadequate for that purpose, the stock being often burst open in attempting to clamp it sufficiently tight by them. The screws, in conjunction with the bail, help to prevent the backward displacement, and the one on which the bail is hinged, forms the fulcrum of the tool. They are, however, employed by me chiefly to support the tool against side-movement, as before explained.

In fig. 2, the bail is represented as consisting of two bars F*, having suitable eyes or rings f* on their lower ends, for the reception of the bosses through which the clamping-screws pass, and at their upper ends, f*¹, threaded, and receiving a cross-bar, F¹, having a V-shaped, or chisel-edge f*², for a bearing-surface, and adjusted on said screws f*¹ by nuts f*³. The tool to which it is applied, is that patented by J. E. Elmer-son, and the one to which my improvements primarily have reference.

Either the spiral or straight cutters may, when desired, be provided with longitudinal, spiral, or irregular circumferential corrugations, or grooves, to adapt the tool for different purposes.

My different improvements are applicable to other gummers, and their form may be further modified, as

required or preferred, without departing from the principle of the invention.

Having thus described my invention,

I claim as new therein, and desire to secure by Letters Patent—

1. The combination of the bail F F*, rotary cutter C, and lever A², employed substantially as and for the purpose set forth.

2. The bail F, when provided with a V, or chisel-shaped bearing-surface, f, substantially as and for the purpose set forth.

3. The adjustable frame, or carriage B, when em-

ployed in combination with the gumming-roller, or cutter O of a saw-gummer, in the manner and for the purpose specified.

4. The clamping-screws G G', in combination with the perforated frame A a' and perforated bail F f', substantially as described.

To the above specification of my said invention, I have signed my hand, this 9th day of July, A. D. 1868.

NELSON JOHNSON.
